FLUSH VALVE

Michael Ward, South Orange, N. J.

Application November 10, 1936, Serial No. 110,055

2 Claims. (Cl. 137—93)

This invention relates to flush valves and deals more particularly with the diaphragm type of valve known as flushometer valve and is an improvement on the structure shown in my application filed December 3, 1935, Serial No. 52,626.

The invention contemplates the provision of an economically constructed, simple, and positive acting valve comprising few parts which are readily and quickly assembled.

Another contemplated feature of the invention resides in the novel construction of the auxiliary tilting valve employed in the device.

A further contemplated feature resides in the main valve being integrally formed with the seat for the auxiliary tilting valve.

The invention has for its further object the provision of novel means for equalizing the pressures in the chambers to each side of the diaphragm.

A still further object resides in the provision of siphon preventing means to obviate the possibility of back-siphonage from the sewage system to the fresh water supply and thus effectively preventing contamination.

With the foregoing features and objects in mind and many others which will later become apparent, the invention resides in the novel constructional details and in their novel combination and arrangement as illustrated in the accompanying drawing in which is depicted an embodiment of the invention as at present contemplated.

In the drawing:

Fig. 1 is a vertical cross-sectional view through a flush valve showing the features of the invention.

Fig. 2 is a transverse sectional view through the main valve sleeve.

Fig. 3 is an enlarged fragmentary sectional detail view showing the improved siphon breaking means.

Fig. 4 is a similar view of an alternate form of pressure equalizing means.

Describing the invention, as embodied in the drawing, in greater detail, the body 5 is preferably of cast metal and is formed with an outer circumferential wall 6 and an inner wall 7 concentrically disposed therein to provide an annular chamber 8 therebetween and a flow passage 9 centrally disposed of the body 5.

The body casting is formed with a water inlet 10 communicating with the chamber 8 and with a water outlet 11 in alignment with the flow passage 9.

5 sage 9.

The upper portion of the wall 6 is provided with an inreaching annular flange 12, and thereabove, said wall is internally screwthreaded as at 13.

Fitted to the body, there is provided a cover member 14 provided with external screw threads 15 for engagement with the threads 13. To insure a leak-proof fit between the body and its cover member, a gasket, such as shown at 16, may be provided.

The cover 14 is formed with an annular ring surface 17 which coacts with the flange 12 to clamp the peripheral portions of a flexible diaphragm 18, and in order to obtain a tight gripping of the diaphragm, the cover is provided with a polygonally-shaped head 19 for accommodation of a wrench or other like tool.

The lower portion of the cover 14, adjacent the surface 17, is reduced in diameter so that an annular chamber 20 is formed between the threaded portion of the body and the mentioned lower portion of the cover. Beyond the peripheral edge of the diaphragm 18, the flange 12 is formed with a bleed hole 21 which thus communicates the chamber 8 with the annular chamber 20.

The mentioned reduced portion of the cover 14 is provided with a horizontal bore 22 in which is fitted a cylindrical plug 23 having a central bleed hole 24 and provided with a rounded seat 30 projecting into the chamber 20. Projecting into the chamber 26 formed between the cover 14 and the diaphragm, there is provided a ball cage 27 having a shank 28 also fitted into the bore 22. The cage is provided with a freely movable ball valve 29, a valve seat 30, a passage 31 connecting the cage chamber with the bleed hole 24, and a port 32 communicating the cage chamber and the chamber 26. This assembly may have any angular disposition with respect to the bleed hole 21.

The main valve sleeve 33 is formed with a valve portion 34 having a sliding fit in the upper portion of the wall 7 and with three guide members 35 which afford equalized guiding of the valve sleeve in its movement within the sleeve wall 7. The upper portion of the valve sleeve is reduced in diameter as at 36 and over this reduced portion is positioned the central portion of the diaphragm 18 which is clamped to the valve sleeve by means such as the nut 37. The mentioned reduced portion is upwardly extended as at 38 to form the seat for the auxiliary valve disc 39.

In the present instance the valve disc is pref-

55

erably made of non-metallic material and is housed in a cup 40. The valve stem 41, which passes through the central passage 42 of the valve sleeve 33, is formed with a threaded shank 5 43 having engagement with the disc holding cup, and with a shoulder portion 44 having an abutting 10 face for retaining the valve disc 39 in its cup.

The cup 40 is formed with a central projection 45 to act as a pilot for the coil compression 15 spring 46 which projects into a recess seat 47 in the cover member 14.

The lower end of the valve stem 41 is formed 20 with a shoulder 48 which serves to support a sleeve 49 movable with the stem and slidably 25 mounted thereon.

The lower portion of the valve sleeve 33 may be threaded as at 50 for the reception of a ring 51. A desired rate of flow through the passage 42 may be had by providing a ring of suitable 20 diameter relative to the diameter of the mentioned passage.

The valve is provided with an operating handle 25 52 having a cam portion 53 disposed within a bonnet 54 which is clamped to the body 5 as by means of the nut 55 threadedly engaged with the cylindrical body projection 56. The handle cam 53 engages the disc portion 57 of a sliding 30 stem 56 adapted for movement in the guide block 59 which is clamped between the bonnet 54 and the projection 56 by the nut 55.

Packing 60 is provided around the stem 58, said packing being housed in a seat in the guide block 60 and retained in position by a gland 61. A compression spring 62 is disposed between the 25 disc 57 and the gland 61 to serve the dual function of retaining said gland in place and for maintaining the stem 58 out of contact with the sleeve 49 until the handle 52 is moved.

The operation of the valve is quite well-known 40 and briefly is as follows: When the handle is moved, the cam 53 moves the stem 58 to engage the sleeve 49 and thus tilt the valve disc 39 off its seat 38. Water from the chamber 26 will then pass into the outlet pipe 63 via the passage 45 42. The release of water from the chamber 26 now allows the water pressure in the chamber 8 to lift the diaphragm 18 and thus the sleeve valve 33. Fresh water from the inlet 10 now pours through the chamber 8, over the top of 50 the wall 7, and through the central passage 9 into the outlet pipe 63. At the same time water is passing through the bleed hole 21, into the annular chamber 20, through the bleed 25 and passage 31, into the ball valve cage 27, and out 55 of the port 32 into the chamber 26. The rate of flow into the chamber 26 is relatively slow, it requiring anywhere between 9 and 12 seconds to fill the chamber 26 depending upon conditions. During this time the flow of fresh water into the 60 outlet continues and the lower end of the sleeve 49 moves with the diaphragm and with the valve sleeve to a point above and out of engagement with the stem 58. This permits the valve disc 39 to again seat itself on its seat 38 to stop 65 discharge of water from the chamber 26. As this chamber fills and the pressure therein equalizes with the pressure in the chamber 8, the diaphragm moves down to seat on the top of the wall 7 and thus breaks the flow from the chamber 8 into the outlet pipe 63. Upon release of 70 the handle 52, the stem will withdraw to allow the sleeve 49 to drop to its initial position on the shoulder 48.

Since flushometer valves are placed in the 75 fresh water supply line which is also tapped for

human consumption, it is essential that no reverse flow be started from the outlet 63 to the inlet line 10. This at times occurs, whether due to suction or to the establishment of a siphon action. It is for the purpose of preventing this 5 reverse flow that the ball valve 29 is provided. Any reduction in pressure in the chamber 8 will ordinarily cause a commensurate reduction in pressure in the chamber 26 with the resultant lifting of the diaphragm from its seat. However, any tendency to reduce the pressure in the chamber 26 when the valved disc 39 is seated will cause the ball 29 to be sucked against the seat 30 and thus to seal the pressure in the chamber 26. Thus it will be evident that the 10 greater the siphoning force on the chamber 8, the more tightly will the diaphragm seat on the rim of the wall 7.

As seen from Figure 4, should siphon breaking means be unnecessary, or should other 20 siphon breaking means be employed, the ball valve may be omitted and merely a small orifice 24^a provided in the skirt portion of the cover 14.

Note should be made of the extremely simple 25 construction of the flush valve as herein disclosed; of the ease with which it may be assembled; of the lack of sensitively adjustable parts; and of the efficient manner of its operations. The present disclosure does not exhaust the structural possibilities and it is conceded that 30 many changes within the scope of the invention as contemplated may well be made by skilled persons. Hence, the prior art, rather than this specific disclosure, should form the basis for determining the scope of the invention as claimed. 35

I claim:

1. In a flushometer valve having a cylindrical wall concentrically disposed to form an annular water inlet chamber; a pressure balancing chamber, a diaphragm between the pressure balancing chamber and the inlet chamber, an in-reaching annular flange on which the outer peripheral margin of the diaphragm rests, an internally screw-threaded portion above the annular flange, a cover member having external 40 screw threads for engagement with said threaded portion, an annular ring surface on the bottom of said cover for cooperation with the flange to clamp said peripheral margin of the diaphragm between it and the flange, the lower portion of said cover being reduced in diameter to provide an annular chamber between the threaded portion of the body and the reduced portion of the cover, the outer circumference of the diaphragm being substantially coextensive with the 45 outer circumference of the reduced end of the cover, said flange having a bleed hole there-through located beyond the peripheral edge of the diaphragm to communicate the inlet chamber with the annular chamber and said reduced 50 portion of the cover having a bleed hole there-through to communicate the annular chamber with the pressure balancing chamber.

2. In a flushometer valve having a cylindrical wall concentrically disposed to form an annular 65 water inlet chamber; a pressure balancing chamber, a diaphragm between the pressure balancing chamber and the inlet chamber, an in-reaching annular flange on which the outer peripheral margin of the diaphragm rests, an internally screw-threaded portion above the annular flange, a cover member having external screw threads for engagement with said threaded portion, an annular ring surface on the bottom of said cover for cooperation with the flange to 70 75

clamp said peripheral margin of the diaphragm between it and the flange, the lower portion of said cover being reduced in diameter to provide an annular chamber between the threaded portion of the body and the reduced portion of the cover, the outer circumference of the diaphragm being substantially coextensive with the outer circumference of the reduced end of the cover, said flange having a bleed hole therethrough located beyond the peripheral edge of the diaphragm to communicate the inlet chamber with the annular chamber and said reduced portion of the cover having a bleed hole therethrough to communicate the annular chamber with the pressure balancing chamber, a valve sleeve slid-

ably fitting within the cylindrical wall, the upper portion of the valve sleeve being reduced in diameter to provide a shoulder, said reduced portion being externally threaded and extending through the center of the diaphragm, a nut 5 cooperating with the sleeve threads to clamp the diaphragm between the nut and the shoulder, a portion of the sleeve extending upwardly beyond the nut and having a rounded edge to provide a seat for an auxiliary valve disc, and 10 an auxiliary valve disc releasably held against said seat and manually operated means to unseat the auxiliary valve disc to reduce the pressure in the balancing chamber.

MICHAEL WARD. 15
